CLAIM

The ornamental design for a shoe, as shown and described herein.

DESCRIPTION

FIG. 1 is a front, right side, top perspective view according to my design for a shoe.

FIG. 2 is a front view of the shoe shown in FIG. 1.

FIG. 3 is a rear view of the shoe shown in FIG. 1.

FIG. 4 is a right side view of the shoe shown in FIG. 1.

FIG. 5 is a left side view of the shoe shown in FIG. 1.

FIG. 6 is a top view of the shoe shown in FIG. 1.

FIG. 7 is a bottom view of the shoe shown in FIG. 1; and, FIG. 8 is a front, right side, bottom perspective view of the shoe shown in FIG. 1.

The broken lines shown on the shoe depict stitching, which does form a part of the claimed design.

The shoe illustrated is a first embodiment showing a left-footed form of the shoe. A second embodiment is for the right-footed form of the shoe, which is a mirror image of the left-footed form, and is not illustrated.
